UNITED STATES PATENT OFFICE.

ST. ELMO BATEMAN, OF LOS ANGELES, CALIFORNIA.

FUMIGATING APPARATUS.

1,426,536.

Specification of Letters Patent. Patented Aug. 22, 1922.

Application filed July 29, 1920. Serial No. 399,649.

To all whom it may concern:

Be it known that I, ST. ELMO BATEMAN, a citizen of the United States, residing at Los Angeles, in the county of Los Angeles 5 and State of California, have invented certain new and useful Improvements in Fumigating Apparatus, of which the following is a specification.

This invention relates to means for raising and lowering canopies, tents and the like, and the primary object of the invention is to provide an improved means for quickly and easily placing and removing canopies over citrus trees and the like, during the treating thereof by fumigating gas for scale and other pests that damage the trees.

Another object of the invention is to provide an improved apparatus embodying a pair of wheel trucks arranged to support an overhead frame, the frame having an improved means associated therewith for permitting a canopy or the like to be quickly raised or lowered over a tree to be treated.

25 A further object of the invention is to provide an improved apparatus for aiding in fumigating of fruit trees and the like which is of such a construction that the same can be readily moved between the rows of 30 trees in an orchard and when in one position can effectively reach four different trees, so that the canopy can be readily placed over or removed from the same without necessitating the repositioning of the 35 apparatus for each tree.

A further object of the invention is to provide an improved apparatus for use in treating of trees in which the frame is adjustable within certain limits and so arranged that trees spaced various distances apart can be effectively reached by the apparatus without necessitating the repositioning thereof, the adjustable frame also permitting the effective treating of trees of 45 various heights and circumferences.

A further object of the invention is to provide an improved means for detachably associating the hoisting cables of the apparatus with the canopy so as to permit the 50 hoisting cables to be readily attached to or detached from the canopy.

A further object of the invention is to provide an improved canopy which has associated therewith in a novel manner a 55 pair of spaced canopy ropes, slidably

mounted in a plurality of eyes carried by the canopy, the canopy ropes being adapted to be detachably connected with the hoisting cables of the apparatus.

A still further object of the invention 60 is to provide an improved apparatus of the above character, which is durable and efficient in use, one that is simple and easy to manufacture, one that can be placed upon the market at a reasonable cost, and one 65 which can be readily taken apart and collapsed for storage or transportation.

With these and other objects in view, the invention consists in the novel construction, arrangement and formation of parts as will 70 be hereinafter more specifically described, claimed and illustrated in the accompanying drawings, forming a part of this specification, in which drawings:

Figure 1 is a side elevation of the improved apparatus showing a canopy positioned over a tree to be fumigated.

Figure 2 is a plan view of the supporting frame.

Figure 3 is a transverse section through 80 the supporting frame.

Figure 4 is a detail fragmentary section taken on the line 4—4 of Figure 3.

Figure 5 is an enlarged fragmentary detail sectional view illustrating the means 85 for associating the transverse bars with the longitudinally extending side bars of the supporting frame.

Figure 6 is a transverse section through the frame illustrating the means for connecting the supporting standards to the 90 frame.

Figure 7 is a detail section taken on the line 7—7 of Figure 6.

Figure 8 is a plan view of the main truck 95 for supporting the frame.

Figure 9 is a detail transverse section through the main truck.

Figure 10 is a transverse section through the forward supporting truck. 100

Figure 11 is a similar view, showing the means for holding the forward truck against movement when the apparatus is in use.

Figure 12 is a plan view of the improved canopy. 105

Figure 13 is a diagrammatic view illustrating the lay out of an orchard and the method pursued in placing the canopies over the trees.

Referring to the drawings, in detail, 110

wherein similar reference characters designate corresponding parts throughout the several views, the letter A generally indicates the improved apparatus and B one of the improved enclosing canopies.

The improved apparatus A includes a main truck C and a forward truck D, a supporting bridging frame E carried by the trucks and the lifting cables F.

10 The main truck C includes a platform or bed plate 5 the opposite ends of which carry suitable supporting axles 6 on which are rotatably mounted the forward and rear wheels 7, which may be provided with suitable tires 8, which may be of the pneumatic variety if so desired.

15 The central portion of the truck is provided with an upstanding bearing 9, the upper surface of which is semi-spherically shaped for a purpose which will be herein-after more fully described. The bearing 9 is adapted to receive the upstanding vertical hollow post 10 the lower end of which is shaped to conform to the configuration of

20 the bearing, and it can be seen that the post is free to swing in said bearing. The upper end of the post 10 is provided with a collar 11, which supports a plurality of right angularly positioned radially extending eyes 12 which have pivotally connected thereto the depending guy rods 13. The guy rods 13 have interposed therein suitable turn buckles 14 whereby their lengths may be adjusted. Two of the guy rods 13 are ar-

25 ranged at the longitudinal center of the truck C while the other two guy rods 13 are arranged at the transverse center of the truck. The two rods 13 which are ar-

30 ranged at the longitudinal center of the truck are connected by a flexible sprocket chain 14, while the other two rods are connected by a flexible sprocket chain 15. Suitable guide wheels 16 are carried by the sides of the truck for receiving the sprocket 35 chains and it can be seen that the sprocket chains pass entirely under the supporting platform 5. The platform 5 supports on its lower surface a longitudinally extending shaft 17 which has keyed or otherwise 40 secured thereto a sprocket wheel 18 which is adapted to engage the sprocket chain 15. The shaft 17 is provided with a suitable crank wheel 19 whereby the same can be rotated. It can be seen that by rotating

45 the crank wheel 19 the sprocket chain 15 will be moved transversely of the truck, and thereby swing the post 10 at an angle to the vertical longitudinal center of the truck. The lower surface of the platform 5 also rotatably supports a transversely extending shaft 21, the outer end of which is provided with a crank wheel 22 for permitting the rotation thereof. The inner 60 end of the shaft 21 is provided with a sprocket wheel 23 which engages the longi-

tudinally extending chain 14 and it can be seen that by turning the crank wheel 22 the sprocket chain 14 will be moved thereby swinging the post 10 at an angle to the vertical transverse center of the truck. This means is provided so that if the truck C is positioned on a hillside or the like, the post 10 can be moved in a perpendicular position. This is easily accomplished by the manipulation of the crank 75 wheels 19 and 22. Suitable releasable locks 24 and 25 are provided for engaging the sprocket wheels 18 and 23 respectively and these releasable locks each include a pivoted lever 26, the free end of which is adapted to engage in the teeth of the sprocket wheels. The opposite end of the pivoted lever is connected to a link 28 which is pivotally connected to the inner end of an operating foot pedal 29. When it is desired to operate the shafts for adjusting the position of the post 10, it is merely necessary to depress the foot pedals 29 and rotate the cranks 19 and 22.

20 The supporting post 10 slidably receives a standard 30 which is adapted to be attached to the overhead frame E which will be hereinafter more fully described. The standard 30 is adapted to be held in any adjusted position by means of a removable pin 31, which is adapted to be placed in any one of a plurality of apertures 32 formed therein. By adjusting the standard 30 the height of the overhead frame E may be regulated in relation to the truck 100 and to a tree which is to be treated.

25 The forward truck D embodies an axle 32 which is rotatably mounted in a suitable bearing sleeve 33 and this bearing sleeve is provided with a pair of upstanding spaced ears 34 between which is positioned the lower flattened end 35 of a supporting post 36. The opposite ends of the axle 32 support wheels 37 which may be provided with tires 38 of the pneumatic type. A draft tongue 39 is provided for the forward truck so as to permit drawing of the apparatus to the trees which are to be treated and this draft tongue includes downwardly extending right angularly disposed feet 40 which are adapted to dig into the ground to prevent accidental movement of the truck D when the frame E is positioned for lifting or lowering one of the canopies B over a tree to be treated. The tongue 39 also supports an angular extending arm 41 which extends in an opposite direction to the feet 40 and this arm is provided with a substantially circular collar 42 which is adapted to rotatably engage the bearing 33. When the truck D has been placed in an adjusted position the tongue 39 is swung downwardly as clearly shown in Figure 11 of the drawings which will throw the feet 40 into engagement with

the ground and raise the wheels 37 off of the ground. The forward end of the tongue 39 engages the upper surface of the ground as will the feet 40 and thus it can be seen that a relatively large bearing surface is provided for the forward truck so as to hold the same against movement. The lower flattened end 35 of the supporting post 36 is pivotally connected to the ears 34 by a pivot pin 43 and thus it can be seen that the supporting post 36 is also free to swing in relation to the forward truck D. This permits the standard 36 to swing in relation to the post 10. The post 36 is of hollow formation and slidably receives a standard 44 which is held in its adjusted position by a suitable removable pin 45 which is extended through any one of a plurality of openings 46 formed therein.

20. The upper bridging supporting frame E includes a pair of spaced longitudinally extending side bars 47 and end bars 48 and 49. The end bar 48 has arranged adjacent thereto a pair of spaced parallel bars 50 and 51 which extend transversely across the frame. The bars 47, 48, 49, 50 and 51 may be formed of any preferred material but the same is preferably formed of piping or the like. The frame E is also braced by suitable guy rods 52 which extend longitudinally of the frame and are connected thereto at the central portion thereof by means of relatively short vertically extending rods 53. The upper ends of the standards 30 and 44 carry transversely extending semi-cylindrical rods 54 which are adapted to engage the transversely extending end bars or cross rods of the frame. The terminals of the semi-cylindrical rods 54 are braced by diagonally extending rods 55, which are connected to the posts 30 and 44 intermediate their ends. The semi-cylindrical rods 54 are detachably held in place by suitable pivoted clips 56 which are connected to the rods 54 as at 57. The free ends of the clips 56 carry teeth 58 which are adapted to engage in suitable notches formed in the cross rod 54. This connection permits the standards 30 and 44 to be 50. swung on the upper frame when the trees are positioned at various distances from each other and it can be seen by swinging back the clips 56 the upper frame can be entirely detached from the standards when desired. The upper frame has also arranged thereon transversely extending hollow pipes 59, one of which is arranged relatively nearer the end of the frame than the other. These hollow rods 59 carry suitable depending feet 60, which are adapted to embrace the longitudinally extending side bars 47, and these feet are held in place by suitable retaining bolts 61. Each of the hollow rods 59 has slidably mounted therein the oppositely extending supporting arms 62,

the outer ends of which are bent angularly as at 63. The upper terminals of the angular ends of the rods 62 support guide pulleys 64 around which are adapted to be trained the hoisting cables for the canopy B. The inner ends of the sliding arms 62 carry upstanding plates 65 which protrude through grooves 66" formed in the hollow rods 59. These plates 65 form guides for the arms and prevent rotary movement thereof in the hollow rods. The arms 62 are also braced by diagonally extending guy rods 66 which have the terminals connected respectively to the upper ends of the angular terminals 63 of the arms and the plates 65. The hollow rods 59 also have secured thereto at the central portion thereof of base plates 66', which have outwardly extending arms 67, which support rollers 68. These rollers 68 also form guides for the hoisting apparatus. The end bars 48 and 49 have also secured intermediate their ends suitable guide pulleys 70 which also are adapted to receive the hoisting apparatus. The hoisting apparatus F includes a longitudinally extending cable 71, the terminals of which hang over the sides of the frame and form the pulling ropes. This longitudinally extending rope 71 is trained around the pulleys 70. Each of the pulleys 64 have 90. trained therearound the hoisting cables 72 and the inner ends of the cables 72 are trained around the guide pulleys 68 and are connected to the longitudinally extending rope 71. The lower terminals of the 95. hoisting cable 72 carry suitable snap hooks or locks 73 which are adapted to engage the canopy B. Thus it can be seen that when either end of the pulling cable is actuated the hoisting cables 72 will be raised. 100

105. The improved canopy B is preferably formed of canvas or the like and is substantially rectangular shaped with the corners thereof cut diagonally as clearly shown in Figure 12 of the drawings. This formation allows the canopy to assume a substantially circular shape when in use, as shown in Figure 1 of the drawings. Arranged longitudinally of the canopy B is a pair of spaced canopy ropes 74 which are slidably 110. mounted in a pair of rows of guide eyes 75 secured to the outer surface of the canopy. The outer ends of these eyes 75 are loosely secured to the canopy by means of ropes 76. The terminals of the canopy 115. ropes 74 are provided with rings 77, which are adapted to be engaged by the snap hooks 73 of the hoisting cables 72. The rings 77 also prevent pulling of the canopy rope through the eyes 75. In Figure 13 is illustrated a layout of an orchard and it can be seen that the trees are arranged in spaced parallel rows, which are substantially equidistant apart. The trees are generally planted 20, 22 or 24 feet apart and the im- 120

125. 130.

proved apparatus is so constructed as to readily treat trees positioned these distances apart.

The improved apparatus A is moved between a pair of spaced rows of trees in the orchard and the main truck C is stopped at a point approximately equi-distant from four of the trees. The front truck D is then pulled around until the frame E is positioned over the first tree. This action is permitted owing to the fact that the standard 30 is rotatably mounted in the post 10. When the front truck D reaches the desired position the tongue 39 is swung downwardly until the feet 40 are forced into the ground, which holds the front truck against movement. Prior to this, one of the canopies B is secured to the hoisting cables 72 by means of the snap hooks 73, which engage in the rings 77. The pulling cables 71 are then operated which elevates the canopy above the trucks. When the forward truck D has been positioned in correct relation to a tree to be treated, the cables 71 are released which permits the canopy to be lowered over the tree. When the canopy has reached its correct position the snap hooks 73 are released from the rings 77. Another canopy is then attached to the snap hooks and the forward truck D is then swung around so as to move the frame E over the adjacent tree in the outside row. This canopy is then lowered over the second tree, after which the apparatus is then moved between the next four trees indicated by the cross mark and the main truck C is positioned equi-distant from these trees. The forward truck D is then moved so as to position the frame E over the first tree of these four after which the truck is moved so as to position the frame over the second tree of these four in the first row. This operation is repeated until all of the trees of the first row are covered with the canopy. As the time required to fumigate a tree is thirty to fifty minutes, by the time the apparatus has reached the last tree in the first row the canopy from the first tree in the first row can be removed. The apparatus is then brought back to the starting point and the truck D is then moved so as to position the frame E over the first tree. The snap hooks 73 are then placed in engagement with the rings 77 and the canopy is lifted off of the first tree. The truck D is then swung around over to the first tree in the second row which will position the frame over the same. The canopy is then lowered over the first tree in the second row after which the forward truck is swung around the second tree in the first row so as to permit the positioning of the frame thereover and the canopy is lifted off of the same. After the canopy is lifted the truck D is swung in front of the second tree in the second row and the canopy is then lowered

over this tree. The whole apparatus is then moved to the second group of four trees and the canopies on the first row are placed on the trees of this group in the second row. This operation is continued until all of the 70 trees in the orchard have been treated.

If the trucks are positioned on a hillside the posts can be readily held and moved to a perpendicular position by operating the cranks 19 and 22 as heretofore described. 75 If a relatively high tree is to be treated the standards 30 and 44 can be readily raised. For trees of a relatively large circumference, it is merely necessary to move the arms 62 outwardly until the desired adjustment has 80 been reached. Where trees are spaced a relatively large distance from each other it is necessary to raise the frame E by moving the standards 30 and 44 on the posts 10 and 36, and the standards are then swung outwardly on the clips 56. It also can be seen that the standard 44 can be readily disconnected from the frame E by opening the clips 56 and the standards can then be brought into engagement with any one of 90 the cross bars 50, 51, and the end bar 48. This also permits of the adjustment of the frame for large and small trees. Owing to the connection of the canopy ropes 74 it can be seen that when the hoisting cables 72 are 95 raised the lower ends of the canopy will be elevated first. After they have been elevated a certain distance the other parts of the canopy will be raised.

From the foregoing description it can be 100 seen that an improved canopy or apparatus has been provided for use in fumigating fruit trees and the like.

Changes in details may be made without departing from the spirit or scope of the invention; but,

I claim:

1. In a tree fumigating apparatus, a pair of spaced trucks, an overhead frame carried by the trucks, means rotatably connecting 110 one end of the frame to one truck whereby the other truck can move around the first truck as a pivot, outwardly extending adjustable arms carried by the frame, and a hoisting and lowering apparatus carried by 115 the adjustable arms.

2. In a tree fumigating apparatus, a pair of spaced wheeled trucks, an adjustable frame carried by the trucks for movement in a horizontal plane, and a hoisting and 120 lowering apparatus carried by the frame.

3. In a tree fumigating apparatus, a pair of spaced wheeled trucks, an overhead frame adjustably carried by the trucks, a hoisting and lowering apparatus carried by the 125 frame, and means for adjusting the width of the frame.

4. In a tree fumigating apparatus, a truck including a body, supporting wheels carried by the body, a bearing carried by the 130

upper surface of the body, a supporting post pivotally mounted in said bearing, longitudinally and transversely extending pairs of guy rods carried by the posts, sprocket 5 chains connecting the pairs of longitudinally and transversely extending rods together, longitudinally and transversely extending rotatable shafts carried by the body, sprocket wheels carried by the shafts arranged to engage the sprocket chains and 10 means for independently operating the shafts.

5. In a tree fumigating apparatus, a pair of spaced wheeled trucks, an overhead frame 15 detachably carried by the trucks, means connecting one end of the frame, to one of the trucks for rotary movement so as to permit the other truck to be swung around the first mentioned truck as a pivot, transversely extending adjustable arms carried by the frame, hoisting cables carried by the arms, and means carried by the cables for detachably engaging a cover for a tree.

6. In a tree fumigating apparatus, a pair 25 of spaced wheeled trucks, upstanding hollow posts carried by the trucks, adjustable standards carried by the posts, an overhead frame, means detachably connecting the standard to the frame, and hoisting cables 30 carried by the frame.

7. In a tree fumigating apparatus, a pair 35 of spaced wheeled trucks, upstanding hollow supporting posts carried by the trucks, means for swinging the posts at an angle to the trucks, means for holding one of the posts in adjusted position, adjustable standards telescopically mounted in said posts, means for detachably connecting the standards to the posts, a frame detachably connected to the upper ends of the standards, outwardly extending adjustable arms carried by the frame, hoisting cables carried 40 by the arms, means detachably connecting the outer terminals of the hoisting cables 45 to a canopy, and pulling cables connected to the hoisting cables.

8. In a tree fumigating apparatus, a main supporting truck including a rectangular shaped body, supporting wheels carried by 50 the terminals of the body, a hollow supporting standard swivelly carried by the central portion of the truck, guy rods carried by the upper end of the post, flexible cables connecting the terminals of the guy rods together, means carried by the truck for engaging said flexible cables for moving the same in relation to the truck, a second truck, 55 a supporting post pivotally carried by the second truck, supporting standards slidably mounted in the supporting posts of the trucks, a removable frame carried by the upper end of the standards, and a hoisting

and lowering apparatus carried by the frame.

9. In a tree fumigating apparatus, a pair 65 of spaced wheeled trucks, an overhead frame, means rotatably connecting one end of the frame to one of the trucks to permit the other truck to move around the first truck as a pivot, a hoisting and lowering apparatus carried by the frame, and means carried by the second mentioned truck for engaging the ground to prevent movement of the truck.

10. In a tree fumigating apparatus, a pair 75 of spaced wheeled trucks, an overhead frame, means rotatably connecting one end of the frame to one of the trucks so as to permit the other truck to move around the same as a pivot, a pivoted tongue carried by 80 the second mentioned truck, and downwardly extending feet carried by the inner end of the tongue arranged to engage the ground when the tongue is moved into engagement with the frame.

11. In a tree fumigating apparatus, a pair of spaced wheel trucks, an overhead frame adjustably carried by the truck, hollow rods arranged transversely of the frame, sliding arms mounted in the hollow rods, pulleys 90 carried by the terminals of the arms, means carried by the arms for preventing rotary movement thereof in the hollow rods, guy pulleys carried by the hollow rod intermediate the ends thereof, hoisting cables 95 trained over said guy pulleys, a canopy, means detachably connecting the canopy to the hoisting cables, and a pulling cable connected to the hoisting cable.

12. In a tree fumigating apparatus, a 100 truck including a body, supporting wheels carried by the body, a bearing carried by the upper surface of the body adjacent to the central portion thereof, a supporting hollow post swivelly mounted in said bearing, longitudinally and transversely extending pairs 105 of guy rods carried by the post, means connecting the pairs of longitudinally extending rods and transversely extending rods together, said means including a sprocket 110 chain, longitudinally and transversely extending rotatable shafts carried by the body, gear wheels carried by the shafts arranged to engage the sprocket chain, means for operating the shafts, means for locking the 115 shafts against rotation, a second truck, a supporting post pivotally carried by the second truck, supporting standards slidably carried by the supporting posts, an overhead frame detachably carried by the standards, 120 and a hoisting and lowering apparatus arranged to detachably engage a canopy.

ST. ELMO BATEMAN.
